UNITED STATES PATENT OFFICE.

ARTHUR E. SMITH, OF PITTSBURG, KANSAS, ASSIGNOR TO CLAUDE A. SMITH, OF PITTSBURG, KANSAS.

MEDICINAL AND ANESTHETIC PACKAGE.

Application filed December 16, 1922. Serial No. 607,892.

To all whom it may concern:

Be it known that I, ARTHUR E. SMITH, a citizen of the United States, residing at Pittsburg, in the county of Crawford and 5 State of Kansas, have invented certain new and useful Improvements in Medicinal and Anesthetic Packages, of which the following is a specification.

As is set forth in my copending application Serial No. 607,391, it is important in the preparation of medicinal solutions to insure that the liquid used is absolutely sterile and pure; that the solution is fresh and uncontaminated and, in the case of 15 nerve blocking work, that the solution is isotonic to the blood.

In nerve blocking work the solution is made up of distilled water, in which are dissolved the chlorides to make a Ringer's solution, a vaso-constricting ingredient such as suprarenin or adrenalin, and an anesthetic such as novocain or anocain.

The importance of having the solution freshly made at the time it is used is well 25 recognized in the dental and medical professions and in the literature relating thereto. See, for example, page 463 of Prinz's textbook entitled "Dental Materia Medica and Therapeutics", third edition:

30 "The practitioner is especially cautioned in regard to the use of local anesthetics in the form of ready made solutions. Solutions of cocaine, even when rendered sterile by fractional sterilization, will not remain so after the contents of the bottle are exposed to the air for a short time. Ready made solutions that are sold in the shops under more or less fanciful names require still greater precautions. The recently enacted pure food 35 and drug act requires that all solutions containing cocaine, eucain, and other similar alkaloids, must be labeled. Most of the many so called safe and reliable anesthetics found on the market contain cocaine or its 40 substitute in various quantities. The addition of adrenalin to a ready made solution not only destroys this alkaloid in a very short time, but the product of its decomposition with the decomposed cocaine makes the 45 solution still more dangerous. The printed formulas that accompany many of the ready made solutions of local anesthetics frequent-

ly show an utter disregard of the pharmacologic action of the individual ingredients, which forces us to conclude that they are a 55 slur on the intelligence of the practitioner who uses such compounds."

The importance of having the solution isotonic to the blood may be appreciated when it is considered that if the solution is 60 not isotonic (i. e. if the salts of the Ringer's solution do not conform in quantity to the corresponding salts of the blood) the osmotic pressure of the solution will be different from that of the surrounding tissues 65 and will cause pathological changes in the blood and tissues that are highly undesirable. (See U. S. Patent 1,243,349 issued to me on the 16th day of October 1917.)

In the copending application I have 70 stated that the invention consists of enclosing within any suitable container, any two or more substances one at least of which is liquid and separating one or more of the substances from the other or others, until 75 the time of use arrives, by a fusible wall of a material which will retain its form and solidity under ordinary temperatures but may be melted at higher temperatures. When the time of use arrives this separating wall is melted by the application of heat 80 and the contents of the package or container are mixed and the package is opened and its contents used.

The present application relates to a particular embodiment of the invention as disclosed in the accompanying drawing wherein:

Fig. 1 is a view partly in side elevation and partly in longitudinal section, of an ampule embodying the invention, showing the liquid and non-liquid contents of the ampule separated by a waterproof, fusible wall;

Fig. 2 is a like view after the ampule has been subjected to heat to fuse the wall and the non-liquid contents have been dissolved in the liquid contents;

Fig. 3 is a view partly in side elevation and partly in section showing the ampule after its contents have been cooled to cause the material which previously formed the fusible wall to solidify; and

Fig. 4 is a view showing the small end of the ampule broken off to permit of the in-

section of the needle of a hypodermic syringe.

Like numerals designate corresponding parts in all of the figures of the drawing.

5 In carrying out the invention I employ a glass ampule 5, the glass of which should be free of alkali and may be of any suitable color. This ampule comprises a body portion 5^a, a neck extension 5^b and a pointed end 5^c. One of the ingredients, designated 6, which may be in the form of tablets, as shown, or may be in the form of a powder or liquid, is placed within the neck extension 5^b and is sealed therein by a plug of chemically pure paraffin 7. The pure, sterile, distilled water 8, occupies the main body 5^a of the ampule and is kept from contact with the non-liquid ingredient by the paraffin plug until the time of use arrives, at which 10 time the ampule as a whole is placed in water in a sterilizer and boiled or is held under running hot water so that the temperature is raised to such a point as to fuse or melt the paraffin plug, which then floats 15 to the position illustrated in Fig. 2 and permits the tablets or powder or liquid, as the case may be, formerly contained within the neck extension, to be mixed with the distilled water.

20 The ampule is then turned to the position illustrated in Fig. 3 and plunged into a glass of cold water or held in cold running water or otherwise chilled which causes the paraffin to solidify, as indicated at 7^b. The ampule is 25 then inverted and its point 5^c is broken off, as illustrated in Fig. 4, to permit the introduction of the needle of a hypodermic syringe for the purpose of withdrawing the contents therefrom.

30 While the invention is particularly useful in dental nerve blocking work it is not necessarily limited thereto but has a wide range of usefulness, for it provides means to enable any physician or dentist to easily 35 and quickly prepare a solution which will have the advantage of being freshly prepared from fresh, sterile, distilled water, irrespective of what the particular material contained in the capsule may be.

40 It will be observed that the transition of the distilled water from the ampule to the hypodermic syringe is without the interposition of any other receptacle. Thus the 45 chance of contamination of the anæsthetic solution is correspondingly reduced. It will further be observed that this result is accompanied by the provision of a freshly made solution and if the non-liquid contents of the neck extension 5^b consist of sodium 50 chloride, calcium chloride, potassium chloride, a vaso-constricting ingredient such as suprarenin or adrenalin hydro-chloride, and an anæsthetic such as novocain or anocain, and if the chlorides are in proper proportion 55 to the distilled water, as is contemplated, then

there will be produced by this article, without intermediate handling, a solution which is isotonic to the blood, which is freshly made and the base of which consists of distilled water of absolute purity; prepared 70 under laboratory conditions and maintained in a vacuum from the time of its preparation to the time of its use. It is manifest that this results in giving to the professional man a solution that is absolutely safe and 75 desirable from every standpoint.

While the invention is particularly useful in dental nerve blocking work as outlined above, it is by no means limited in its usefulness to that field and it is to be understood that it includes within its purview a container provided with a wall of fusible material which divides the container into two parts, one part of the container receiving one or more ingredients of the finished 80 solution and the other part of the container receiving one or more of the remaining ingredients, the fusible wall serving to keep these ingredients separated until the time of use. For example, digitalis deteriorates 85 quickly and the ampule of the present invention could be employed to receive in the larger part of its body the necessary amount of distilled water and in the smaller part, the necessary amount of digitalis, the two 90 being separated by the fusible wall until the time of use.

Furthermore while all of the chlorides of Ringer's solution are desirable in the preparation of a true physiologic-isotonic solution, 100 sodium chloride alone may be used but the results are not as satisfactory as when all the Ringer chlorides are employed.

While I have described the fusible wall as consisting of a material, such as paraffin, which will separate out of the final solution, the invention includes any suitable material, whether it separates out or not. However, the paraffin has been found to be 105 highly satisfactory and its use is contemplated.

Having described my invention what I claim is:

1. A device of the character described consisting of a two part container, one of which parts contains a liquid ingredient and the other of which contains a non-liquid ingredient and a water-proof wall within the container and separating the said ingredients, said wall being of a material fusible 115 at temperatures above normal but materially below the fusion point of the material of the container.

2. A sealed glass ampule divided into two compartments separated by a wall of water-proof material, one of said compartments containing sterile, distilled water and the other of said compartments containing an anæsthetic ingredient in non-liquid form, said wall being fusible under temperatures 125 130

materially above normal but materially below the fusion point of the glass of the ampule.

3. A sealed glass ampule comprising a large body portion and a relatively smaller neck extension, a non-liquid anæsthetic in the neck extension, distilled water in the body portion and a plug of water-proof material at the juncture of the two compartments, said plug being fusible under temperatures materially above normal but at temperatures materially below the fusion point of the ampule.

4. A sealed glass ampule comprising a large body portion and a relatively smaller neck extension, a non-liquid anæsthetic in the neck extension, distilled water in the body portion and a plug of chemically pure paraffin between the two compartments.

20 5. A sealed glass ampule comprising a neck extension at one end and a pointed end at the other, said neck extension receiving an anæsthetic ingredient in non-liquid form and the body of the ampule receiving distilled water and a plug of a material fusible under temperatures materially above normal but at temperatures materially below the fusion point of the ampule, said plug separating the non-liquid anæsthetic from the

30 water until the ampule is heated.

6. A glass ampule comprising a neck extension at one end and a pointed end at the other, said neck extension receiving an anæsthetic ingredient in non-liquid form and the body of the ampule receiving distilled water and a body of chemically pure paraffin separating the anæsthetic from the

water, the material of the ampule being fused to hermetically seal the same.

7. A device of the character described consisting of a two part container, the compartments of which are separated from each other by a wall of material fusible at temperatures materially above normal but at temperatures materially below the fusion point of the material of the container.

8. A device of the character described consisting of a two compartment ampule and a fusible water-proof plug separating said compartments and meltable at temperatures materially below the fusion point of the material of the ampule, the two parts of the ampule containing ingredients both of which are non-miscible with the material of the plug.

9. A device of the character described consisting of a two part ampule and a fusible water-proof plug separating the two parts of the ampule, the two parts of the ampule containing ingredients both of which are non-miscible with the plug and one at least of which is a liquid, the material of the plug being fusible at temperatures materially above normal but materially below the fusion point of the material of the ampule.

10. A sealed glass ampule comprising two compartments containing, respectively, two substances of which the mixture is unstable in composition, and a wall of material fusible at a temperature between 45 and 100 degrees centigrade, separating said compartments.

In testimony whereof I affix my signature.

ARTHUR E. SMITH.
